UNITED STATES PATENT OFFICE

2,654,328

JOINT FOR ROOFING OR LIKE SHEETS

Patrick E. McCullough, Chicago, Ill.

Application September 27, 1951, Serial No. 248,598

3 Claims. (Cl. 108—22)

1

The present application relates to modifications of the structure of a joint for roofing or like sheets, disclosed in my co-pending application, filed January 28, 1948, Serial No. 4,761, now Patent No. 2,571,273, granted October 16, 1951.

The present invention has substantially the same objects in view as stated in my said co-pending application.

The invention consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views;

Fig. 1 is an end view of a joint made in accordance with the present invention; and

Fig. 2 is a perspective view of a pair of metallic sheets with preformed joint edges in the position immediately preceding to their interengagement and interlocking.

Referring to the present drawing in detail there is shown therein a pair of sheets 10 and 11. The marginal edge of sheet 10 is suitably formed for effecting a complementary part of the joint to be engaged by a complementary part of the joint formed at the marginal edge in sheet 11, in order that the two parts may interengage and interlock when the sheets are brought to an edge to edge relation. Said complementary part of the joint in sheet 10 includes hook 12 which is formed out of the body of sheet 10 by doubling the same upon itself for effecting stem 13, and hook proper 14, which extends from said stem 13, and is inclined toward the body of sheet 10, for the purpose hereinafter described.

The free marginal portion of sheet 10, past said hook 12, is rolled in an upward direction for defining a substantially cylindrical rib 15, the free edge of said rib 15 overhanging said hook 12, and with stem 13 thereon substantially defining a peripheral continuation of the body portion of said rib 15. It is noted that the hook proper 14 extends outwardly of rib 15.

The marginal portion of sheet 11 is suitably preformed for engaging and interlocking the same with the joint part of sheet 10 hereinabove described. Said marginal portion of sheet 11 includes an arcuate, upwardly projecting portion 16, from which flap 17 projects on a plane substantially parallel with the continuation plane of the body portion of sheet 11, as is clearly seen in Fig. 2.

2

The free edge of said flap 17 is bent downwardly, and then into a reverse direction in parallelism with the body of said flap 17, for the purpose of defining hook 18. To engage sheet 10 with sheet 11, rib 15 of the former is brought under flap 17 and toward the upper, arcuate portion 16 of sheet 11, until said rib 15 contacts with said portion 16, as seen in Fig. 1. Thereupon flap 17 is bent downwardly and around said rib 15, and hook 18 is forced in engagement with hook proper 14, as seen in Fig. 1. When hook 18 engages hook proper 14 the joint parts of the two sheets will be interengaged and interlocked, and will form a seal quite impervious to water.

If desired, filler 19, which may consist of a cylindrical rod made of wood or any other suitable material, may be inserted within rib 15 and left in the joint for adding thereto a degree of rigidity, and preventing denting of the joint. Filler 19 may be used in the process of formation of rib 15 and thereupon left therewithin.

Optionally strip 20, made of rubber or any other impervious flexible material, may be rigidly affixed to rib 15, in a longitudinal relation therewith and along the uppermost point of its periphery, for providing a seal between the said rib and the contacting inner face of the outer cylinder defined by said flap 17 when the latter is bent around said rib 15, as seen in Fig. 1, thereby preventing seepage of liquid, such as water, which may otherwise enter the joint and pass below the plane of sheets 10 and 11.

Although rib 15 preferably is of an annular formation on a transverse cross section, it is understood that it need not be restricted to that formation, but may be polygonal if desired. Flap 17, however, should be preformed to correspond to the formed contour of rib 15 in order that the two may closely contact.

To maintain hook 12 rigidly in its formed formation, and prevent its distortion when under engagement by hook 18, the base of stem 13 may be spot welded, as at 21.

The two sheets 10 and 11, with the joint therebetween may be rigidly affixed to the roof base in any suitable manner. If desired, angle iron 22, in a longitudinal relation with the joint aforesaid may be affixed to sheet 11, by spot welding 23, or other suitable means. Said angle iron 22 may then be super-imposed upon joist 24 and engaged therewith by any suitable means.

While there is described herein a preferred embodiment of the present invention, it is nevertheless to be understood that minor changes may be

made therein without departing from the spirit and scope of the invention as claimed.

What I claim as new is:

1. A joint for a pair of sheets along their contacting edges comprising a generally cylindrical rib extending along one edge of one of said sheets, a hook projecting from the surface of said sheet and on the same side thereof as said rib, said hook being turned away from said rib, an arcuate upwardly extending marginal portion along the edge of the other of said sheets, a flap extending from said arcuate portion and in an integral relation therewith, and a hook extending along the marginal free edge of said flap, said hook being turned toward said arcuate portion in position to engage the hook on said first mentioned sheet when said flap is bent in an embracing relation with said rib.

2. A joint for a pair of sheets along their contacting edges comprising a generally cylindrical rib extending along one edge of one of said sheets, a hook projecting from the surface of said sheet, the stem of said hook being substantially on the peripheral arc of said rib, the hook proper being turned away from said rib, an arcuate upwardly extending marginal portion along the edge of the other of said sheets, a flap extending from said arcuate portion and in an integral relation therewith, a hook extending along the marginal free edge of said flap, said hook being turned toward 30

said arcuate portion in position to engage the hook on said first mentioned sheet when said flap is bent in an embracing relation with said rib, and sealing means extending along said rib and located between said rib and said flap.

3. A joint for a pair of sheets along their contacting edges comprising a generally cylindrical rib extending along one edge of one of said sheets, a hook projecting from the surface of said sheet, the stem of said hook being substantially on the peripheral arc of said rib, the hook proper being turned away from said rib, an arcuate upwardly extending marginal portion along the edge of the other of said sheets, a flap extending from said 10 arcuate portion and in an integral relation therewith, and a hook extending along the marginal free edge of said flap, said hook being turned toward said arcuate portion in position to engage the hook on said first mentioned sheet when said 15 arcuate portion and said flap are in an embracing relation with said rib when said flap is bent there-around.

PATRICK E. McCULLOUGH.
